PACKAGING TRAY

Robert M. Nelson, 27 Drayton Place, Wayne, N.J.

Filed Dec. 30, 1964, Ser. No. 83,545

Term of patent 14 years

(Cl. D58—12.6)

Fig. 4.

Fig. 5.

Fig. 6.

FIG. 1.

FIG. 1 is a top plan view of a packaging tray embodying my new design wherein each side wall includes three upstanding fingertips, the high end walls extend in generally straight fashion across the ends of the narrow tray, and the upper edge of the end walls includes an outwardly directed flange;

FIG. 2 is a side elevational view of the packaging tray of FIG. 1;

FIG. 3 is an end elevational view of the packaging tray of FIG. 1;

FIG. 4 is a top plan view of a modified form of a packaging tray embodying my new design;

FIG. 5 is a side elevational view of the packaging tray of FIG. 4;

FIG. 6 is an end elevational view of the packaging tray of FIG. 4;

FIG. 7 is a top plan view of another modified form of a packaging tray embodying my new design;

FIG. 8 is a side elevational view of the packaging tray of FIG. 7; and

FIG. 9 is an end elevational view of the packaging tray of FIG. 7.

The characteristic feature of my new design resides in the combination, in packaging trays of the configuration illustrated, of a narrow and substantially flat bottom tray

FIG. 5.

FIG. 9.

having rather steep upwardly flaring side walls, the upper edge of the side walls being convoluted by means of gently curving lines to resemble the plurality of spread-apart upwardly directed fingertips spanned by interconnecting webs, and the narrow tray having rather steep upwardly flaring end walls which join with the convoluted side walls and which extend higher above the flat bottom than do the fingertips of the convoluted side walls.

This is continuation-in-part of copending application Serial No. D. 78,022, filed January 2, 1964, now abandoned.

I claim:

The ornamental design for a packaging tray, as shown and described.
